Primary Examiner — Cathron Brooks*Assistant Examiner* — Christian P McLean(74) *Attorney, Agent, or Firm* — Reising Ethington P.C.(57) **CLAIM**

The ornamental design for a vehicle front fascia, as shown and described.

DESCRIPTION

FIG. 1 is a perspective view of the vehicle front fascia;
FIG. 2 is a left side elevation view thereof;
FIG. 3 is a top plan view thereof; and,
FIG. 4 is a front view thereof.

The right side elevation view of the vehicle front fascia is omitted because the right side elevation view is identical to the left side elevation view. And the broken lines shown in the drawings depict portions of the vehicle front fascia that form no part of the claimed design.
